[57] CLAIM

The ornamental design for a wood type golf club head or similar article, substantially as shown and described.

DESCRIPTION

FIG. 1 is a front view of a wood type golf club head showing our new and ornamental design.

FIG. 2 is a back view of the club head of FIG. 1.

FIG. 3 is a top view of the club head of FIG. 1.

FIG. 4 is a bottom view of the club head of FIG. 1.

FIG. 5 is a view of the club head of FIG. 1 from the toe.

FIG. 6 is a view of the club head of FIG. 1 from the heel.

FIG. 7 is a modified form of the front view of the golf club head of FIG. 1.
